UNITED STATES PATENT OFFICE

108,403

DESIGN FOR A BEDSPREAD

Gerhardt H. Rauschenberg, Dalton, Ga.

Application January 12, 1938, Serial No. 74,227

Term of patent 3½ years

To all whom it may concern:

Be it known that I, Gerhardt H. Rauschenberg, a citizen of the United States of America, residing in the city of Dalton, State of Georgia, have invented a new, original, and ornamental Design for a Bedspread, of which the following is a specification, reference being had to the accompanying drawing, forming part thereof, wherein, the figure is a plan view of a bedspread, showing my new design.

I claim:

The ornamental design for a bedspread, substantially as shown.

GERHARDT H. RAUSCHENBERG.
